United States Patent Office

Des. 188,408
Patented July 12, 1960

188,408

PLASTIC COATED FABRIC

John C. Siegmann, Toledo, Ohio, assignor to The Landers Corporation, Toledo, Ohio, a corporation of Ohio

Filed Sept. 2, 1959, Ser. No. 57,412

Term of patent 14 years

(Cl. D87—3)

The figure shows a plan view of a plastic coated fabric embodying my new design.

I claim:

The ornamental design for a plastic coated fabric, substantially as shown.
